SYSTEM FOR PICKLING

Ernest C. McHenry, Leechburg, Pa., assignor to
 Allegheny Ludlum Steel Corporation, Bracken-
 ridge, Pa., a corporation of Pennsylvania

Application January 26, 1952, Serial No. 268,442

5 Claims. (Cl. 134—122)

1

This invention relates to rolls and in particular to a system utilizing hold-down rolls for use in pickling baths of steel mills.

According to prior steel mill practice, strip material of stainless and other types of steels is passed through a pickling solution to remove scale from the surfaces thereof. In order to maintain the strip immersed in the pickling solution hold-down rolls have been widely used, the hold-down rolls being so mounted with respect to the pickling tank that the lower portion of the roll is in the pickling solution and the strip of steel passes beneath but in contact with the roll, the roll thereby maintaining the strip immersed in the pickling solution.

The rolls are usually formed of a metallic housing having a coating of rubber or other elastomer applied thereto in adhering relation to protect the metallic housing from the acid of the pickling solution. However, in practice it is found that the elastomer protective coating is often cut or otherwise punctured by reason of burs or rough or uneven edges found on the strip material which is being treated.

Under such circumstances when the protective coating is punctured the acid is admitted into contact with the metallic housing with the result that the metal of the housing is attacked and destroyed without any evidence to the operator of the destruction of the roll until such destruction has advanced to the point that the roll collapsed and it was impossible to repair it. Since the pickling step is usually only one portion of a continuous annealing and pickling operation it is appreciated that the destruction of one of the hold-down rolls effects a complete shutdown of the continuous operation of treating the metal strip until the roll could be replaced with a new roll.

An object of this invention is to provide, in a hold-down roll for a pickling line, for limiting damage to the roll when the protective coating thereof is punctured or otherwise cut to admit acid to the metallic portions of the roll.

Another object of this invention is to provide for limiting damage to the metallic housing of a hold-down roll when the protective coating thereof is punctured and to simultaneously provide for indicating such limited damage so that the roll can be repaired.

Other objects of this invention will become apparent from the following description when taken in conjunction with the accompanying drawing in which:

Fig. 1 is a view in side elevation and partly in 55 .10 to .20% carbon grade and is provided with a

2

section of apparatus embodying the teachings of this invention;

Fig. 2 is a view in section, greatly enlarged, of a portion of the apparatus of Fig. 1; and

Fig. 3 is a view in section, greatly enlarged, of a portion of the roll of Fig. 2 illustrating the limiting of damage to a roll embodying the teachings of this invention.

Referring to Fig. 1 of the drawing this invention is illustrated by reference to apparatus utilized for pickling the surface of a strip 10 of stainless or other type of steel. The apparatus includes a tank 12 formed of an outer metallic housing 14 and having a layer 16 of rubber or the like disposed over the inner surface thereof for protecting the metal housing 14 of the tank from the action of a pickling solution 18. The pickling solution may be any of the well known pickling solutions, such as a 4 to 6% hydrofluoric acid solution, or 10 to 14% nitric acid solution, or up to a 20% solution of sulfuric acid, the pickling solution 18 being usually maintained in a heated condition at a temperature of between 140 to 200° F. The pickling solution 18 usually fills the tank 12 to a level represented at 19 closely adjacent its upper edges.

Associated with the tank 12 are guide rolls 20 and 22 at the opposite upper ends thereof over which the strip 10 passes as it enters and emerges 30 from the pickling solution 18.

In order to hold the strip 10 immersed in the pickling solution 18 as it passes from the roll 20 to the roll 22 one or more so-called "hold-down" rolls 24 and 26 are disposed in mounted relation 35 with the upper edge of the tank 12 so as to be supported thereon, the lower edge of the hold-down rolls 24 and 26 being immersed in the pickling solution 18 as illustrated in Figs. 1 and 2 and in contact with the strip 10. While in this embodiment only two hold-down rolls 24 and 26 are illustrated, it will, of course, be appreciated that the number of hold-down rolls will depend upon the length of time it is desired to maintain the strip immersed in the pickling solution 18 40 as well as the speed with which the strip 10 is drawn through the pickling solution 18 and the condition of the surfaces of the strip 10.

Referring to Fig. 2 of the drawing the structure of the roll 24 is illustrated it being understood that the structure of roll 26 and other hold-down rolls which are used in conjunction therewith will be the same. As illustrated the hold-down roll 24 comprises an inner metallic housing 28 usually formed of common steel of the

shaft 30 which, in the embodiment illustrated, extends through the metallic housing and is provided with projecting ends 32 and 34. The shaft 30 and the metallic housing 28, the latter being of any desirable diameter, are welded into an integral leak-proof structure, such procedure being so well known that it is unnecessary to illustrate such welding. Since the roll 24 is to operate partially immersed in the pickling solution 18, the outer surfaces of the metallic housing 24 and at least a portion of the projecting ends 32 and 34 of the shaft 30 are provided with a protective layer 36 of rubber, synthetic rubber or other elastomer, the protective layer 36 effectively covering the entire metallic surface of the housing 28 and the welded joints (not shown) between the shaft 30 and the metallic housing. The elastomers, polychlorobutadiene and polyisobutylene, or the modified isobutylene synthetic rubbers are other examples of elastomers satisfactory for use as the protective layer 36. The layer 36 is applied in adhering relation to the housing 28 and the shaft 30 by any of the well known methods such methods being so well known that they need not be described herein. As illustrated the extension of the protective layer 36 outwardly along the outer ends 32 and 34 of the shaft 30 is provided with outwardly extending annular projections 38 and 40, respectively, which projections function to prevent runoff of the pickling solution from the main body of the roll 24 outwardly along the projecting ends 32 and 34 of the shaft 30 so as to prevent the solution's coming in contact with the exposed metallic portions of the projecting ends 32 and 34 of the shaft 30.

In accordance with this invention each of the projecting ends 32 and 34 of the shaft 30 are so drilled as to provide passageways 42 and 44, respectively, from a point at the outer end of the projecting ends of the shaft inwardly of the metallic housing 28. The purpose of such passageways 42 and 44 will be explained more fully hereinafter.

In order to mount the pickling roll 24 in operative relation with respect to the pickling solution 18, the metallic casing 14 of the tank 12 is provided with outwardly extending flanged edges 46 and 48 at its upper edge thereof for receiving bearing housings 50 and 52, respectively, such housings being provided with bearings 54 and 56, respectively, for receiving the projecting ends 32 and 34, respectively, of the shaft 30.

In most instances the hold-down roll 24 is of the idler type, that is, no power is applied to the roll 24 for effecting rotation thereof, the rotation in the bearings 54 and 56 being effected merely by the frictional contact of the strip 10 with the lower portion of the roll 24. However, in some instances it may be desirable to apply driving power to the roll 24 and for this reason the roll 24 is illustrated in Fig. 2 as being disposed for having driving power applied thereto. Thus the mounting assembly at the opposite ends of the shaft are so illustrated that power can be applied to the shaft 30 at the end of the projecting end 32, although it will be understood that if power is not to be applied thereto then the projecting end 32 may be formed and mounted in the same manner as the projecting end 34 of the shaft 30.

As illustrated in Fig. 2 in order to supply water or other fluid medium to the hold-down roll 24, the purpose of which will be explained more fully hereinafter, a coupling 57 is provided at the end of projecting end 34 of the shaft. Thus

a terminal plate 58 is disposed to be secured as by means of the hold-down bolts 60 to the bearing housing 52, a suitable gland packing 62 being provided and disposed about the end of the projecting end 34 and bearing 56 to prevent leakage thereabout. The terminal plate 58 is provided with a suitable threaded opening 64 disposed in alignment with the passageway 44 in the projecting end 34 of the shaft 30. A suitable conduit 66 is connected in threaded engagement with threaded opening 64 for connecting such threaded opening to a source of water or other fluid supply as represented by the pipe line 68 in Fig. 1. When so connected water or other fluid is supplied internally of the roll 24, preferably under pressure of ten or more pounds per square inch, the purpose of which will be more fully explained hereinafter.

Where the other projecting end 32 of the shaft 30 is disposed to have power applied thereto, an opening 70 is drilled through the shaft into registry with the passageway 42, the end of the passageway 42 being plugged as by means of a threaded stopper 72. In such a structure a coupling 73 comprising a terminal plate 74 seated against an annular ring 76 having a threaded passage 78 therein, is secured to the bearing housing 50 as by means of the bolts 60. As in the other example, a suitable packing 82 is provided between the terminal plate 74, annular ring 76, bearing 54 and the projecting end 32 of the shaft 30 for effecting a leak-proof seal therebetween. Power can be applied by any suitable mechanism (not shown) to the end of the projecting end 32 of the shaft 30 which extends beyond the terminal plate 74. As illustrated a standpipe 84 is disposed in threaded engagement with the threaded opening 78 of the annular ring 76 to permit escape of the water or other fluid medium from the housing through the passage 42, openings 70 and 78 and the standpipe 84, suitable means such as a catch basin 86, as illustrated in Fig. 1, being provided for receiving and carrying the fluid away from the standpipe 84 as the fluid is discharged therefrom.

If instead of applying power to the projecting end 32 of the shaft 30 the roll 24 is to be operated as an idler roller, then the simpler coupling structure illustrated as applied to the end of the projecting end 34 of the shaft may be utilized instead of the more complicated coupling structure illustrated as applied to the projecting end 32 of the shaft 30, the difference being that the standpipe 84 would be substituted for the supply pipe 66.

Where a plurality of the hold-down rolls are employed, such as rolls 24 and 26, the couplings 57 thereof are usually connected to a common source of water supply such as the pipe 68 and the standpipes 84 discharge into similar catch basins 86 in the manner illustrated in Fig. 1.

With the structure formed and assembled as described hereinbefore the strip 10 of metal is passed over a roll 20 and beneath the hold-down roll 24, and other hold-down rolls where such are used, immersed in the pickling solution 18 and emerges from the pickling solution 18 over the roll 22. In operation, water or other fluid medium is supplied under pressure from the source as represented by the conduit or pipe 66 through the conduit 66 and passageway 44 of the projecting end 34 of the shaft 30 internally of the metallic housing 28 of the roll 24. The standpipe 84 at the other end of the shaft 30 is of a sufficient height to prevent escape of the

water or other fluid from the housing 28 until the housing is completely filled with the fluid medium. In practice the standpipe 34 is usually provided with a height of about seven feet so as to insure that the housing 28 is completely filled with the fluid medium.

As the strip 10 passes underneath the roll 24 in contact with the protective layer 36 thereof, if burrs on the edge of the strip or unevenness of an edge of the strip punctures or cuts the layer 36 of elastomer into the metal surface of the housing 28, it is found that the acid of the pickling solution 18 will penetrate such puncture or cut in the layer 36 as the roll 24 rotates with an edge thereof in the solution 18. The acid admitted through such a puncture, illustrated in Fig. 3 as being shown at 88, contacts the outer surface of the metallic housing 28 and so attacks such metal as to effect a destruction thereof over an area closely adjacent the puncture 88. The area so attacked is illustrated in Fig. 3 as at 90 and is shown as being slightly larger at the outer surface of the metallic housing 28 than the area of the puncture 88 and is usually found to decrease in size towards the inner surface of the metallic housing 28 as the acid eats through the metallic housing 28. As soon as the acid of the pickling solution 18 succeeds in penetrating the metallic housing 28 to the extent that an opening is formed therethrough as represented at 90, the water or other fluid medium under pressure within the metallic housing 28 flows through the opening 90 and the puncture 88 thereby effectively so diluting the acid present on the exposed surface of the metallic housing as to prevent further attack thereby on the metallic housing and the pressure of the fluid medium within the housing 24 effectively prevents any further admission of the pickling solution through the puncture 88 so as to prevent further attack by the acid of the solution on the metallic housing 28. Simultaneously with the flow of the fluid medium through the zone of the destruction 90 and the perforation 88 it is found that because of the pressure of the fluid medium such fluid medium actually sprays outwardly through the puncture 88 so that as the roll 24 rotates to expose the puncture above the level of the pickling solution 18, the spray 92, as illustrated in Fig. 2, gives a visible indication of such a puncture and of the start of the destruction of the metallic housing 28 of the roll 24.

When such a signal is given steps should be taken to repair the damaged surface of the protective layer 36 of the housing 24 although since the flow of the fluid medium outwardly through the opening 90 and puncture 88 prevents further attack by the acid of the metallic housing 28, the line need not be shut down immediately to effect such a repair. In practice such repairs can often be made by a simple vulcanization of the elastomer layer at the point of puncture and thereafter dressing or smoothing the repaired surface without having to remove the roll 24 from its assembled relation with the pickling tank 12 thus effecting further economies in the maintenance of the pickling line. It will also be appreciated that the opening 90 can be repaired by a simple weld prior to repairing the puncture in the layer 36.

The invention has effected considerable economies in the operation of continuous annealing and pickling lines for strip material as it prevents complete destruction of the hold-down rolls

with the resultant saving in the cost of the roll per se, the visible indication of the start of such a destruction making it possible to correct damage to the outer protective layer of the roll without too great an interpretation in the continuous operation of the mill. Maintenance costs of the rolls in one pickling line have been reduced as much as 80% through the installation of the system of this invention.

10 While reference has been made herein to strip material it is of course to be understood that such term has been employed generically as applying to a continuous strip or to a plurality of sheets suitably tack welded or otherwise secured together.

I claim:

1. In a system for holding metallic strip material in an acid solution as the strip passes therethrough, the combination comprising, a hold-down roll having a metallic housing, a shaft having projecting ends for supporting the housing, a layer of elastomer disposed in adhering relation over the metallic housing and covering at least a portion of the projecting ends of the shaft 20 adjacent the housing, the elastomer on the housing being disposed to contact the strip material and being subject to being punctured thereby during use, the shaft having an opening through each end thereof into the housing, a source of water under pressure, one of the openings being connected to the source of water, the other of the openings being disposed to drain the water from the housing, and means connected to said other of the openings to control the level 30 of the water in the housing to maintain the housing filled with water under pressure, the water within the housing limiting damage to the housing, when the elastomer layer is punctured and admits acid, to the area of the housing closely 35 adjacent to the area of the puncture.

2. In a system for holding metallic strip material in an acid solution as the strip passes therethrough, the combination comprising, a hold-down roll having a metallic housing, a shaft having

45 projecting ends for supporting the housing, a layer of rubber disposed in adhering relation over the metallic housing and covering at least a portion of the projecting ends of the shaft adjacent the housing, the rubber on the housing 50 being disposed to contact the strip material and being subject to being punctured thereby during use, the shaft having an opening through each end thereof into the housing under pressure, a source of water, couplings connected to the projecting ends of the shaft in communication with the openings therein, one of the couplings being connected to the source of water for admitting water through the opening associated therewith to fill the housing, the other of the couplings 55 cooperating with the opening associated therewith to provide a drain for the housing, and a standpipe connected to said other of the couplings, the standpipe having a height sufficient to insure maintaining the housing filled with

60 water under pressure, the water within the housing limiting damage to the housing, when the rubber layer is punctured and admits acid thereto, to the area of the housing closely adjacent to the area of the puncture.

65 3. In a system for holding metallic strip material in an acid solution as the strip passes therethrough, the combination comprising, a rotatable hold-down roll having a metallic housing, a shaft having projecting ends for supporting the housing, a layer of elastomer disposed in

adhering relation over the metallic housing and covering at least a portion of the projecting ends of the shaft adjacent the housing, the elastomer on the housing being disposed to be immersed in the acid solution as the roll is rotated in contact with the strip material and being subject to being punctured thereby during use, the shaft having an opening through each end thereof into the housing, a source of water under pressure of at least ten pounds per square inch, one of the openings being connected to the source of water, the other of the openings being disposed to drain the water from the housing, and means connected to said other of the openings to control the level of the water in the housing to maintain the housing filled with water under pressure, the water within the housing limiting damage to the housing, when the elastomer layer is punctured and admits acid, to the area of the housing closely adjacent to the area of the puncture and providing a visible indication of said damage as the roll is rotated.

4. In a system for holding metallic strip material in an acid solution as the strip passes therethrough, the combination comprising, a rotatable hold-down roll having a metallic housing, shaft means disposed to extend from the opposite ends of the housing for supporting it, a layer of elastomer disposed in adhering relation over the metallic housing and covering at least a portion of the shaft means at the opposite ends of the housing, the roll being disposed to be supported with respect to the acid solution whereby the elastomer on the housing is immersed in the acid solution as the roll is rotated in contact with the strip material, the elastomer being subject to being punctured by the strip material during contact therewith, the shaft means at the opposite ends of the housing having openings therethrough into the housing, a source of water under pressure, one of the openings being connected to the source of water to admit water into the housing, the other of the openings being disposed to drain the water from the housing, and means connected to said other of the openings to control the level of the water in the housing to maintain the housing filled with water under pressure, the water within the housing limiting damage thereto, when the layer of elastomer is punctured and admits acid, to the

area of the housing closely adjacent to the area of the puncture and providing a visible indication of said damage as the roll is rotated.

5. In a system for holding metallic strip material in an acid solution as the strip passes therethrough, the combination comprising, a rotatable hold-down roll having a metallic housing, a shaft disposed through the housing with the ends of the shaft extending outwardly therefrom for supporting the housing, a layer of elastomer disposed in adhering relation over the metallic housing and covering at least a portion of the extending ends of the shaft adjacent the housing, an annular projection of elastomer carried by the elastomer cover of each of the extending ends of the shaft, the elastomer on the housing being disposed to be immersed in the acid solution in contact with the strip material and being subject to being punctured by the strip during use, the annular projections of elastomer carried by the extending ends of the shaft being disposed to limit the extent of flow of acid solution outwardly from the housing to only the covered portions of the ends, the shaft having an opening through each end thereof into the housing, a source of water under pressure, one of the openings being connected to the source of water to admit water into the housing, the other of the openings being disposed to drain the water from the housing, and means connected to said other of the openings to control the level of the water in the housing to maintain the housing filled with water under pressure, the water under pressure within the housing limiting damage thereto, when the layer of elastomer is punctured and admits acid to the metallic housing, to the area of the housing closely adjacent the area of the puncture, the water under pressure within the housing also providing a visible indication of said damage to the housing as the roll is rotated.
